UNITED STATES PATENT OFFICE.

EDWIN E. BARNEY, OF NEW ROCHELLE, NEW YORK, AND JOSEPH PHELPS, OF NORTH CALDWELL, NEW JERSEY, ASSIGNEES TO REMINGTON TYPEWRITER COMPANY, OF ILION, NEW YORK, A CORPORATION OF NEW YORK.

TYPEWRITING MACHINE

Application filed June 21, 1923. Serial No. 646,942.

To all whom it may concern:

Be it known that we, EDWIN E. BARNEY and JOSEPH PHELPS, citizens of the United States, and residents, respectively, of New Rochelle, in the county of Westchester and State of New York, and North Caldwell, in the county of Essex and State of New Jersey, have invented certain new and useful Improvements in Typewriting Machines, 10 of which the following is a specification.

Our invention relates to tabulating mechanism for typewriting machines and its general object is to provide a decimal tabulating mechanism including stop setting and unsetting devices which is unusually simple and compact.

To the above and other ends which will hereinafter appear, our invention consists in the features of construction, combinations 20 of devices and arrangements of parts hereinafter described and particularly pointed out in the claims.

In the accompanying drawings which illustrate the preferred form of our invention, 25 Figure 1 is a fragmentary front-to-rear vertical sectional view of a typewriting machine embodying our invention.

Figure 2 is a horizontal sectional view taken on a plane designated by the section 30 line 1—1 in Fig. 1 and looking downward in the direction of the arrow at said line.

Figure 3 is a fragmentary perspective view of the tabulating mechanism.

Figure 4 is a horizontal sectional view 35 taken on a plane designated by the section line 2—2 in Fig. 1 and looking in the direction of the arrow at said line.

Figure 5 is a plan view showing the set 40 of column stops on their support, the decimal stops also being shown.

Figure 6 is a fragmentary front elevation of the keys of the tabulating mechanism and their mounting.

Figure 7 is a fragmentary operating view 45 of the stop setting devices.

Figure 8 is a corresponding view of the unsetting or stop retracting devices.

Figure 9 is a detail perspective view.

In the drawings only so much of a typewriting machine is shown as is necessary 50 fully to understand the present invention, but the said machine is disclosed in greater detail in some respects in the patent to Barr

and Barney # 1,433,112, granted October 24, 1922. The main frame of said machine as 55 appears from Fig. 1 of the present drawing comprises side plates or frame members 1 preferably formed with openings and connected at the rear by a cross plate 2. A U-shaped frame member 3 is connected to 60 the front portions of the side plates 1 and incloses the keyboard. Above the main frame is arranged a platen 4 which is mounted on a carriage comprising end bars 5 connected by an inclined bar or plate composed of upper and lower grooved portions 6 and 7 and connecting cross webs 8, the whole constituting the rear bar of the carriage. The carriage is mounted through 65 roller bearings 9 on fixed guide-ways, the 70 rollers co-operating with the grooved parts 6 and 7 of the carriage and with stationary upper and lower grooved trackways 10 and 11 at opposite ends of an angular bed plate or trough 12, said trough being suitably 75 secured to the top portions of the side plates 1 at their rear. The carriage is constantly urged leftward by a spring drum or motor (not shown), to which it is connected by a band or strap 13, under the control normally 80 of escapement devices which operate through connecting mechanism comprising a feed rack 14 on the carriage and which constantly meshes with a feed pinion 15 mounted on a horizontal shaft 16 supported on the 85 bed plate. The feed pinion is loosely mounted on said shaft but is normally connected to turn therewith in printing direction through devices connecting said pinion with a toothed escapement wheel 17 fixed to said 90 shaft 16. Said devices comprise a spring pressed pawl 18 pivoted to the escapement wheel and which normally engages with the teeth of the feed pinion 15. The escapement wheel is normally dogged or prevented 95 from turning by devices comprising a dog 19 whereby the carriage is held from moving from right to left under the impulse of its motor. The carriage may be released from the control of the escapement mechanism by 100 devices operative to separate the pawl 18 from the feed pinion 15, said devices comprising a sleeve 20 slidably mounted on the escapement wheel shaft and provided with flanges 21 spaced apart near its rear and 105 also with a front flange 22 beveled to co-

operate with a pin 23 fixed to the pawl 18 and projecting rearward therefrom through a slot in the escapement wheel. Said sleeve 20 is controlled from the novel tabulating mechanism by devices presently to be described.

In order to make the tabulator mechanism as compact and unobtrusive as possible, we preferably mount the column stops 10 inside the machine, as it may be termed in contrast with the usual mounting outside of the machine. To this end a pair of angular brackets 24 are arranged one near each end of the carriage, beneath the rear bar 6-8 15 (Figs. 1 and 5). The brackets are formed with holes 25 which receive headed screws 26 whereby they are secured to the carriage and depend from its rear. At their lower ends the brackets are perforated to receive 20 the reduced rounded bearing portions 27 of a toothed stop bar 28, the ends of the reduced portions being threaded to accommodate nuts 29. It will be observed that 25 the stop bar is covered by the carriage and is slightly above the lower carriage bearing. The stop bar is formed at its upper and lower faces with kerfs or cuts 30 providing teeth at letter space intervals, which teeth receive between them a set of column 30 stops 31. These column stops are of ordinary construction being U-shaped so as to fit over the stop bar between the teeth at the top and bottom thereof and being provided with rearwardly projecting stop faces 35 31^a. Pivoted at 32 to the side of each stop bar is a yoke-like spring member 33 terminating in end stops 34 and 35 (Figs. 1, 5, 7 and 8). When in inoperative position forward on the stop bar each stop 31 40 is held by the co-operation of the stop end 35 with the lower corner of the stop bar 28 in the position shown in Fig. 8, this position corresponding with that of most of the stops in Fig. 5 and also with that of the stop 45 nearest the observer in Fig. 1. Thus maintained the stops are in inoperative position or "unset" as it is sometimes termed. To set these stops or position them for co-operation with the key actuated decimal stops 50 they are selectively slid rearward in a manner hereinafter described. During this sliding movement the spring or retaining member 33 swivels or turns slightly on its pivot 32, enabling the stop end 35 to clear the 55 lower corner of the stop bar and permit rearward sliding movement of the stop 31 on said bar until arrested by co-operation of the stop end 34 with the top front corner of the stop bar as shown in Fig. 7. In 60 other words, the stops 31 are projectible or slidable rearward on their support to operative position and are also retractable or slidable forward on their support to inoperative or "unset" position. The stop setting and retracting means comprise key 65

controlled devices hereinafter described and which are associated with the key operated decimal stops.

The decimal or denominational stop devices are mounted on a tabulator frame 70 which in turn is detachably mounted on the machine. Said tabulator frame comprises a casting 36 having a hooded top portion 37 and depending side arms 38 which curve outward at their lower ends and are 75 connected by an angular cross bar 39 (Figs. 1, 2 and 3). Detachably secured to the front upper portion of the hood 37 by screws 40 is a comb plate 41 provided at its top with a rib or projection 42, the front of 80 said comb plate being provided with upper and lower combs 43 and 44 for guiding the decimal stops. The lower portion of the comb plate is undercut or off-set rearward from the upper portion. The frame comprising the casting 36 and the comb plate 41 supports a set of decimal stop levers as well as certain of the stop setting and un-setting devices, all these parts being attachable and detachable with the frame. When in 85 place on the machine, the frame 36, 41 rests on the top of the frame bar 2, the ledge 2^a at the top of said bar 2 providing a convenient seat for the horizontal portion of the cross bar 39 of the frame. The bed plate or trough 12 is cut out to accommodate the hooded upper portion 37 of the detachable frame, the cut-out of said bed plate indicated at 45 being at the right-hand side of the escapement shaft 16. The upper edge of the 90 cut-out 45 is formed with a square-cut groove or depression to receive the rib 42 at the top of the detachable frame 36, 41. After said rib has been fitted in its groove, thus 95 securing the upper end of the frame, the lower end portion or cross bar 39 receives headed screws 47 which are threaded into the ledge 2^a, thus rigidly securing the detachable tabulator frame in place. The 100 decimal stop levers 48, of which there are 105 ten in the present instance, are vertically arranged within the frame or casting 36, their upper end portions curving forward within the hood and terminating in forwardly extending heads or stop portions 110 proper 49 which are adapted to slide through the combs 43 and 44 and are guided thereby in their movements into and out of operative position. The upright stop levers 48 are pivoted near their upper ends on a 115 cross rod 50 which extends from side to side of the frame 36 and has its ends supported by the side arms 38 of said frame. Spacing washers 51 may be secured on the 120 pivot rod 50 to keep the stop levers 48 properly separated from each other. Below their pivotal support the stop levers spread or fan laterally outward and their lower portions are received in slots or guide openings 125 indicated at 52 formed in a guide plate or 130

comb 53 that is horizontally disposed and extends forward beneath the cross bar 39, the plate 53 terminating at its rear in an upstanding portion 54 which is secured as 5 by rivets 55 to the rear face of the vertically disposed portion of the cross bar 39. Above the cross bar each lever 48 is provided with a rearwardly projecting lug 56 over which fits the forward end of a coiled restoring 10 spring 57, the rear end of said spring being housed in a hole 58 formed in the vertical part of the cross bar 39, the rear end of the spring abutting against the part 54 which covers the hole at the back. The springs 57 15 tend to swing the lower arms of the stop levers 48 forward and the upper arms backward, maintaining the stop blades or heads 49 in retracted or inoperative positions within the hood 37, the rear edges of the stop 20 levers normally resting against a stop bar 59 secured within the hood. The lower ends of the stop levers 48 are curved rearward and slightly forward, terminating in rounded noses 60. 25 Co-operative with the noses 60 are a set of key operated slide rods 61, one for each stop lever 48, the slide rods being arranged within the base in parallelism and extending fore-and-aft of the machine, being supported at both rear and front by detachable 30 supporting members. Each slide rod 61 terminates at its rear end in a hook-like portion comprising a flattened vertically disposed upright portion 62 and a forwardly 35 extending horizontal guide portion 63. The hook-like portions of the slide rods are supported and guided by a U-shaped guide bar 64 terminating in ears 65 which receive screws 66 that are threaded into bosses 2^b 40 on the cross plate 2. The upper and lower edges of the cross portion of the guide bar 64 are formed with slots or depressions indicated respectively by the numerals 67, 68, the lower slots 68 receiving and guiding the 45 rear portions of the slide rods proper 61 while the upper slots 67 support and guide the forwardly extending portions 63 of the slide rods and prevent the rods from turning on their axes. Each upright flattened 50 portion is opposite the associate nose 60 against which it is adapted to act when the rod 61 is slid rearward to actuate the associate lever 48. The front ends of the slide rods 61 are supported and guided by a sheet 55 metal guide plate or frame 69 which in cross section is of an inverted U-shape (Figs. 1 and 6). The guide frame 69 is secured by screws 70 to the front of the frame member 3 of the machine, the screws being accessible through holes 71 formed in the front portion or plate of the guide frame. The end portions of the front plate or flange 69^a are cut away so as to expose the end portions of the rear plate or flange 69^b, these 60 end portions providing tabs 72. The upper cross portion of the frame 69 is inclined forward and downward and has secured to it by screws 73 a slotted index plate 74 under which may be arranged a suitable number strip containing indicia which are exposed 70 through the slot in the plate 74. The forward ends of the slide rods 61 project forward beneath the bottom edge of the frame plate 3 and receive finger pieces 75. These finger pieces are cylindrical in shape and 75 may be made of fiber, some suitable composition, or other desired material. The rear faces of the finger pieces 75 have metal disks 76 pressed or otherwise secured in them, said disks having tapped holes which co-operate with the threaded forward ends of the slide rods 61 to detachably secure the finger pieces or keys 75 to said slide rods. The front flange or plate of the frame 69 is formed with holes indicated at 75^a of a 80 suitable size to permit of the passage therethrough of the keys 75, the rear end portions of said keys normally resting on the bottoms of said holes which serve as guides for the keys as they slide through during 85 operations of the tabulating mechanism. When one of the keys 75 is pushed in, its slide rod 61 will be moved or slid longitudinally rearward, causing the flat portion 62 to press against the nose 60 of the associate 90 stop lever 48 and swing said lever on its pivot 50, projecting its upper or stop end 49 forward into the path of those of the column stops 31 which have been "set" or projected rearward on their supporting bar 28. 95 The actuation of one of the decimal stop levers 48 by its key 75 is effective automatically to release the carriage from the control of its escapement devices, the releasing 100 means comprising, as shown in Figs. 1 to 4, a universal bar 77 arranged horizontally behind the levers 48 somewhat below their pivotal axis. Said universal bar is provided with up-turned ears 78 which receive screws 79 that fasten the universal bar to the lower 105 ends of arms 80 comprised in a supporting frame which further includes a cross bar 81 connecting the arms 80, said arms being angularly bent from the cross bar which extends across the set of levers 48 at their front. The upper ends of the arms 80 receive pivot screws 82 which are threaded into the sides of the arms 38 and provide a pivotal support for the frame 80, 81 and the universal bar member 77, 78 carried 110 thereby. The lower ends of the arms 80 are squared off and rest in contact with the upper face of the universal bar 77 so that the latter is held in rigid relationship with its supporting frame. The left-hand arm 80 has an upward extension 83 which is curved or bent leftward and terminates in a horizontally disposed finger or engaging portion 84 which fits between the flanges 21 of the sleeve 20. When one of the stop levers 48 115 120 125 130

is actuated by its key 75 the lower arm of said stop lever swinging rearward about its pivot will contact with the front edge of the universal bar 77, swinging the latter rearward on its pivots 82 and causing the finger 84 pressing against the forward flange 21, to slide the sleeve 20 forward so that the beveled flange 22 acting against the pin 23, will lift the pawl 18 from the pinion 15, thereby releasing the carriage. It will be observed from Fig. 1 that the universal bar 77 lies normally some distance behind the rear edges of the levers 48 so that the universal bar will not be actuated until the latter part of the stroke of said levers, giving time for the associate stop 49 to be positioned before the carriage is released. When the tabulator key is released, permitting the actuated parts to be restored to normal position, the tabulator universal bar 77 and connected parts will likewise be restored to normal position through the operation of a coiled restoring spring 85, the rear end of which is seated in a depression 86 in the back wall of the hood 37, the front end of said spring fitting over a lug or projection 87 on the universal bar.

The stop setting devices whereby the column stops 31 may be projected or slid rearward on their supporting bar 28 into operative or set positions are shown in Figs. 1, 2, 3, 6, 7 and 8 and comprise a crank arm 88 terminating at its free end in a rounded nose which lies just forward of the lower branches of the column stops 31. Said crank arm is provided with a hub 89 which fits over and is secured to the left-hand end portion of a horizontal rock shaft 90, having a stationary bearing 91 projecting upward from the horizontal portion of the bed plate 12. Fixed to the right-hand end portion of the rock shaft 90 outside its bearing is a downwardly projecting arm 92 having a curved or cam face 93 which is adapted to be acted against by the forwardly projecting nose 94 of a stop setting lever 95. Said lever is of the general shape of the set of levers 48 and is arranged at the right of said set and inside the right-hand casting arm 38 to which the lever 95 is pivoted at 95^a. The lower arm of said lever 95 is guided in a slot of the plate 53 and terminates in a nose 96 which is adapted to be acted on by the flat vertical portion 97 of a slide rod 98 which also has an upper guiding portion 98^a, said slide rod 98 corresponding in construction with the slide rods 61 and being disposed at the right of said set of slide rods, the slide rod 98 being guided in the right-hand pair of guide slots 67 and 68. The front end portion of the slide rod 98 passes through a guide opening in the right-hand tab 72, being guided and supported thereby. Fixed to the front end portion of the slide rod

98 is a "stop set" key or button 99. When the stop set key 99 is pressed in, its slide rod 98 will be slid rearward, actuating the stop setting lever 95 and causing the nose-like upper end portion 94 of said lever, acting against the cam edge 93, to rock the shaft 90 and swing the crank arm 88 rearward, causing said crank arm to press rearward against the lower branch of that particular column stop 31 which may lie opposite to said crank arm at the time, and sliding said stop rearward or "setting" it as has been described. It will be apparent that it is only necessary to move the carriage endwise to position to bring the desired column stops in line with the stop setting arm 88 and then to operate the stop setting key 99, in order to set the desired column stops in position for use. In Fig. 5 several column stops are shown as set or projected in position for co-operation with the set of decimal stops, heads or blades 49 when these are projected or swung forward into position as indicated by the dotted lines at one of the decimal stops 49. It should here be noted that since the set of decimal stop levers 48 is off-set to the right of the middle of the machine to clear the escapement devices, it is necessary correspondingly to off-set the set of column stops, this being done of course by adjusting the position of the column stop bar 28 in correspondence with the off-setting of the frame 36 of the decimal stops. The universal bar 77 is cut away at its right-hand end at 77^a behind the lever 95 so that the stop setting mechanism will not actuate the carriage releasing mechanism; and there is a similar cut-out 77^a at the left-hand end of the universal bar.

The stop retracting, or "unsetting" devices as they are sometimes called, comprise a cam arm or wiper 100 horizontally disposed and pivoted at its right-hand end, which is bent laterally rearward, on a pivot pin 101 mounted on a lug 102 on the right-hand face of the hood 37 and projecting downward from said lug. The arm 100 extends leftward across the front of the lower part of the comb plate 41 and under the overhanging portion thereof. Said comb plate is provided near its left-hand free end portion with a double cam face 103 which is in line with the stop portions 31^a of the column stops. At its left-hand end the arm 100 is provided with a rearward extension or finger 104, best shown in Fig. 9, which serves as a guide and support for the wiper member 100—104 in co-operation with a guide slot 105 cut in the left-hand end of the comb 41 and a second guide slot 106 formed or cut in a thickened portion of the hood 37 at its left-hand side (Fig. 9). When the cam or wiper 100 is swung horizontally back and forth it is 130

prevented from sagging or getting out of position by the guide finger 104 co-operating with its guide slots. Said cam member is actuated by a lever 107 arranged at the left of the set of levers 48 and generally conforming in shape to said levers, being guided by the left-hand one of the slots 52, but having a separate pivot 108 supported by the left-hand arm 38. The upper portion or head of the lever 107 differs, however, from the heads 49 of the levers 48, said lever 107 having a wider head or end portion 109 which fits in a special wide slot 44^a in the comb plate 41. Below the head 109 the lever 107 is provided with a forwardly extending hook 110 whose upturned end lies under the cam portion 103 of the arm 100, said cam portion being undercut to provide a shoulder 111, with which the hook 110 may co-operate. It will be seen, more especially from Fig. 8, that the upturned end of the hook 110 lies just in front of the shoulder 111 while the lower end of the head 109 lies just behind the arm 100, there being an open space 112 between the head or blade and the hook. The construction is such that the arm 100 is thus loosely connected with the lever 107 by which it is positively actuated in both directions, said arm being adapted to be swung forward by the lower end of the head 109 and being adapted to be swung backward by the action of the hook 110 on the shoulder 111. The means for operating the lever 107 for this purpose comprises a slide rod 113 which is similar in construction to the slide rod 61 and is arranged at the left-hand end of the set of slide rods. The slide rod 113 is provided with an upright actuating portion 114 opposite the lower end of the lever 107 and also with a guide portion 115, the rear end portion of said rod and its guide portion 115 co-operating respectively with the left-hand lower and upper slots 68 and 67 in the bar 64. The slide rod 113 extends forward and bears in an opening in the left-hand tab 72, being provided forward of said tab with a key or button 116 by which it may be actuated. When the retracting or "unset" key 116 is pushed in, it will slide the rod 113 rearward, causing it to actuate the lever 107 which will be swung on its pivot 108. Said lever 107 being opposite the left-hand cut-out 77^a in the universal bar 77 will not actuate said universal bar and consequently will not effect the release of the carriage. As the upper arm of the lever 107 swings forward from the position shown in Figs. 1 and 7 to the position shown in Fig. 8, the blade 109 acting against the arm 100 will swing the latter on its pivot 101 and carry the double cam or wiper 103 into position for co-operation with the projected column stops 31 be-

low their stop portions 31^a. Consequently if the operator maintain the "unset" key 116 pressed in, and at the same time release the carriage by hand and move it back and forth or from one side to the other, the double cam or wiper 103 will act on the projected or set column stops 31 to slide them back on their stop bar or towards the front of the machine to "unset" or inoperative position, thus clearing the tabulating mechanism so that a new setting of the column stops may readily be effected by operations of the stop setting key 99 in the manner which has been described. 75

It will be observed that by reason of the fact that the stop set key 99 and unset key 116 bear in tabs 72 at the ends of the rear part or flange 69^b of the front guide plate, they may be disposed in a plane back of the decimal keys 75 which bear in the front flange 69^b, the result being that the decimal keys are separated from the others and the liability of actuating the wrong keys by mistake is reduced. 80

It will be seen that by our present invention there is provided an unusually compact and simple decimal tabulating mechanism which includes devices for setting the column stops and also retracting or "unsetting" them; that said tabulating mechanism is readily attachable to the typewriting machine and detachable therefrom; and that it does not greatly add apparently to the size of the machine since the column stop devices instead of being outside as is usual, in this case are arranged within the machine, so to speak, being disposed under the carriage and between it and its bed plate or trough. 95

Various changes may be made without departing from our invention. 105

What we claim as new and desire to secure by Letters Patent, is:—

1. In tabulating mechanism for typewriting machines, the combination of a traveling carriage, a stationary trough in which said carriage runs, a stop bar in said trough, stops on said stop bar, and a key controlled co-operating stop projective through an opening in said trough. 110

2. In tabulating mechanism for typewriting machines, the combination of a traveling carriage comprising an inclined rear bar, brackets secured to the under side of said rear bar, a stop bar on said brackets at the under side of said inclined carriage bar, stops on said stop bar, and a key actuated co-operative stop. 120

3. In a typewriting machine, the combination with the main frame of the machine of an angular bed plate fixedly mounted thereon, trackways on said bed plate, a traveling platen carriage comprising an inclined rear bar provided with grooved ways, rollers cooperative with said ways, a stop bar ar- 125

- ranged in the space between said inclined rear bar and said angular bed plate, stops on said stop bar, and key operated decimal stops projective through an opening in said bed plate.
4. In a typewriting machine, the combination with the main frame of the machine, of an angular bed plate fixedly mounted thereon, a traveling platen carriage slidably mounted on said bed plate, a stop bar on said carriage, stops on said stop bar, a frame detachably connected with said bed plate, a set of decimal stops mounted on said detachable frame, and a set of keys connected with said stops and operative to project them through an opening in said bed plate.
5. In a typewriting machine, the combination with the main frame of the machine of an angular bed plate fixedly mounted thereon, a traveling platen carriage slidably mounted on said bed plate, a stop bar on said carriage, stops on said stop bar, an upright frame provided at its top with a rib detachably engageable with a groove in said bed plate, means for securing the lower part of said upright frame to the main frame of the machine, a set of vertically disposed decimal stop levers supported on said upright frame, and key controlled means for projecting said decimal levers through an opening in said bed plate.
6. In a typewriting machine, the combination of a traveling platen carriage, column stops on said carriage, a frame detachably supported on the main frame of the machine, a set of key operated decimal stops mounted on said detachable frame, a key operated stop setting device for setting said column stops mounted on said detachable frame, and a key operated retracting device for the column stops also mounted on said detachable frame, the decimal stops and the stop setting and retracting devices being adjustable in place on said detachable frame outside the machine, and being detachable from the machine together with said frame without affecting their relative adjustments.
7. In a typewriting machine, the combination with the main frame of the machine, of an angular bed plate fixedly mounted thereon, a traveling platen carriage slidably mounted on said bed plate, a stop bar on said carriage, column stops on said stop bar, a frame detachably connected with said bed plate, a set of upright decimal stop levers on said detachable frame, a column stop setting lever on said detachable frame, and a column stop unset lever on said detachable frame.
8. In a typewriting machine, the combination of a traveling platen carriage, a stop bar on said carriage, column stops on said stop bar, a detachable tabulator frame, a set of upright decimal stop levers on said detachable frame, a column stop setting lever on said detachable frame, a column stop unset lever on said detachable frame, a column stop unset lever on said detachable frame, a wiper cam on said detachable frame operative by said stop unset lever, and an arm mounted on a stationary part and operative by said stop setting lever to set said column stops.
9. In a typewriting machine, the combination of a traveling platen carriage, column stops on said carriage, a tabulator frame detachably connected with the machine, a set of upright decimal stop levers on said detachable frame, a column stop setting lever on said detachable frame, a column stop unset lever on said detachable frame, and a wiper cam member pivotally supported on said detachable frame and loosely engaged by said stop unset lever.
10. In a typewriting machine, the combination of a traveling platen carriage, column stops on said carriage, a tabulator frame detachably connected with the machine, a set of upright decimal stop levers on said detachable frame, a column stop setting lever on said detachable frame, a column stop unset lever on said detachable frame provided with a head and a hook portion, and a cam arm for unsetting the column stops controlled by said head and hook portions and movable positively back and forth by said unset lever.
11. In a typewriting machine, the combination with the main frame of the machine, of an angular bed plate fixedly mounted thereon, a traveling platen carriage slidably mounted on said bed plate, a stop bar on said carriage, column stops on said stop bar, a frame detachably connected with said bed plate, a set of upright decimal stop levers on said detachable frame, a column stop setting lever on said detachable frame, a column stop unset lever on said detachable frame, and stop setting devices mounted on said bed plate and operative by said stop setting devices comprising a rock shaft, a crank arm fixed to one end portion of said rock shaft, and a cam fixed to the opposite end portion of said rock shaft.
12. In a typewriting machine, the combination of a traveling carriage, escapement devices from which said carriage is releasable, carriage releasing devices comprising a slidably supported sleeve, an angular bed plate mounted on the frame of the machine and on which the traveling carriage is slidably supported, column stops on the carriage, a frame detachably connected with said bed plate, a set of key operated decimal stop levers mounted on said detachable frame, and a releasing frame pivotally supported on said detachable frame and comprising a cross bar extending transversely of said decimal stop levers and further comprising a finger operative on said sleeve.
13. In a typewriting machine, the com-

- bination of a releasable traveling carriage, carriage releasing devices comprising a slidably supported sleeve, column stops on the carriage, a set of key operated decimal stop levers, stop setting and stop retracting devices comprising a pair of levers mounted with the set of decimal stop levers, and a releasing frame comprising a universal bar extending transversely of all of said levers 10 and operative on said sleeve, said frame being cut out opposite said stop setting and stop retracting levers.
14. In a typewriting machine, the combination of a traveling carriage, column stops on said carriage, a frame detachably supported on the main frame of the machine, decimal stop levers mounted on said detachable frame, stop setting devices on said detachable frame, stop retracting devices on said detachable frame, and key members detachably supported on the main frame of the machine for actuating said decimal stop levers, said stop setting devices, and said stop retracting devices.
- 25 15. In a typewriting machine, the combination of a traveling carriage, column stops on said carriage, a frame detachably supported on the main frame of the machine, decimal stop levers mounted on said detachable frame, stop setting devices on said detachable frame, stop retracting devices on said detachable frame, a pair of detachable guides supported on the main frame of the machine, and key-carrying slide rods 30 on said guides, certain of said slide rods actuating said decimal stop levers, and others of said slide rods actuating said stop setting and retracting devices.
- 40 16. In tabulating mechanism for typewriting machines, the combination of a traveling carriage, column stops thereon, co-operating decimal stop levers, slide rods for actuating said levers, said slide rods being provided with keys at their front ends, and a guide plate for the key ends of said rods 45 secured to the frame of the machine and comprising two flanges and a connecting inclined portion, the front flange being formed with holes for said keys.
17. In tabulating mechanism for typewriting machines, the combination of a traveling carriage, column stops thereon, co-operating decimal stop levers, slide rods for actuating said levers, said slide rods being provided with keys at their front ends, a 50 guide plate secured to the frame of the machine and comprising two flanges and a connecting inclined portion, the front flange being formed with holes for said keys, and an index plate secured to the inclined portion 55 of said guide plate.
18. In tabulating mechanism for typewriting machines, the combination of a set of decimal slide rods provided with keys, a stop setting slide rod, a stop retracting slide rod, and a sheet metal guide member comprising a front flange, a rear flange and a connecting portion, the front flange being provided with holes for the decimal slide rods, and the rear flange being provided at 60 its ends with guide openings which receive the stop setting and stop retracting slide rods, the front flange being cut away opposite said stop setting and stop retracting slide rods.
- 75 Signed at the borough of Manhattan, city of New York, in the county of New York and State of New York, this 19th day of June, A. D. 1923.
